UNITED STATES PATENT OFFICE.

HENRY A. WISE WOOD, OF NEW YORK, N. Y., ASSIGNOR, BY MESNE ASSIGNMENTS, TO WOOD & NATHAN COMPANY, OF NEW YORK, N. Y., A CORPORATION OF NEW YORK.

MACHINE FOR PRINTING FROM INTAGLIO PRINTING-PLATES.

1,074,765.

Specification of Letters Patent.

Patented Oct. 7, 1913.

Application filed April 23, 1906. Serial No. 313,118.

To all whom it may concern:

Be it known that I, HENRY A. WISE Wood, a citizen of the United States, residing at New York, in the county of New York and 5 State of New York, have invented a new and useful Machine for Printing from Intaglio Printing-Plates, of which the following is a specification.

My invention relates to a printing press 10 having means whereby intaglio surfaces can be used for printing instead of, or in connection with, relief surfaces such as are ordinarily used.

The invention while capable of general 15 use is especially applicable for use in color printing.

Reference is to be had to the accompanying drawings forming part of this specification and illustrating the invention as applied to a three-color printing press in 20 which,

Figure 1 is a side elevation partly in section of a press with one form of my improvements applied thereto. Fig. 2 is a sectional view on an enlarged scale of a portion of the press showing additional details. Fig. 3 is a side elevation of the gearing, and Figs. 4 and 5 are fragmentary views of a portion of Fig. 1 showing the 25 parts in two different positions.

In the form of press illustrated, an impression cylinder *a*, of the two-revolution type is employed. In such a machine as this, the cylinder constitutes means for supporting individual sheets to be printed and makes two revolutions for each sheet 30 printed, one revolution to print and one to deliver. The cylinder is provided with grippers *b* which, upon reaching the point *c* at 35 which the sheets are delivered, grip them and carry them around the cylinder in the direction of the arrow. I have shown a plurality of printing cylinders *d*, *e*, and *f*, any one or more of which can be employed 40 for printing. In the three-color presses, each cylinder is provided with plates and in accordance with my invention, some or all 45 of these plates are of the intaglio character.

The printing is all done during one 50 revolution of the impression cylinder and during the next revolution, the grippers release the sheet upon the cylinder and deliver it to the strippers *g* and tapes *h* with which the machine is provided, so as to carry it

to the fly fingers *i* which deliver in any desired manner. On this revolution, the grippers do not take on a sheet at the point *c*. The plate cylinders *d*, *e*, and *f* carry printing plates which can be in the form of shells, small plates, or blocks, approximately 55 the size of the several designs. These plates are held on the cylinders in the usual or any desired manner. The plate cylinders may be moved up to the impression cylinder and kept there during the printing 60 revolution and moved away from it during the delivery revolution. This movement may be accomplished in the usual manner by means of connections *k* and eccentrics *l*, or the like. 70

The cylinders may be driven by gearing *m*, indicated in Fig. 3, so as to make a plurality of revolutions to each impression which they give off and they are preferably made adjustable along slots *n* by means of 75 bolts *o*; also by means of collars and screws connected with the ends of the shafts upon which the cylinders are mounted. The plate cylinders are adjustable toward and from the impression cylinder by means of screws 80 *p* and adjusting nuts *q*, or any other convenient form of adjustment may be employed.

The inking of the plates is accomplished by means of rolls *r* which run in a trough 85 of ink.

In connection with the cylinder at the right end of Fig. 1 a roll *s* is shown applying ink to the inking roll *r*, this construction being provided for the purpose of 90 giving more room for the fountain. When the ink is applied to the plates by means of the rollers described or in any other manner, it fills the design of the intaglio plate and all surplus must be wiped or 95 scraped off. For this purpose I have provided a series of blades *t*, each one being held in contact with the surface of its cylinder, preferably by means of a counter-weight *u*, the blade and counter-weight being 100 pivotally mounted on a shaft *v*.

In printing from intaglio plates the non-printing surface must obviously be kept immaculately clean because it comes against portions of the sheet which are to be kept 105 white. If in printing several colors one after the other, the ink from the first color is deposited on the second plate, it will mix

with the ink in the second color, which is of course injurious. I have therefore provided means for preventing this. I have shown this means in the form of blades *w* 5 pivotally mounted on shafts *x* and provided with counter-weights *v*, the construction being similar to the blades *t* and their connections. The counter-weights keep the blades yieldingly in contact with the cylinders. It will of course be noticed that the blades *w* are not necessarily used on the first plate cylinder but are used on all the others.

As has been stated above, the plate cylinders move out of printing position before the delivery revolution of the impression cylinder commences.

It will be noticed that the blades *t* are shown as being mounted on the left-hand side of the cylinders while the blades *w* are on the right-hand side. When the plate cylinders move away from the impression cylinder at the beginning of the delivery revolution thereof, they will move toward one of the blades. I have indicated the cylinders in such position that the one at the left should move to the left while the others move to the right during the delivery revolution of the impression cylinder. In order, 20 if it is desired, to provide for keeping the scraping blades out of contact with the plate cylinders during the idle revolutions thereof and thus reducing the wear, I have provided a roller *z* connected with each of the 25 two shafts *x* and a similar roller is also connected with the left-hand shaft *v*. These rollers are mounted on arms on the shafts, which are shorter than the arms carrying the cleaning blades and the rollers are, in 30 such position as to bear on the plate cylinders at a point between the shaft and the point at which the scraper bears on the cylinder, consequently when the cylinder moves in that direction, it will move the roller a 35 certain distance and the point of the scraper a greater distance and keep the scraper away from the plate cylinder as is clearly indicated in Fig. 5. On the opposite side of the cylinders except the first one, the blade *t* is 40 so located that the cylinder can move away 45 from it, but in order to prevent the counter-weight from turning the scraper into such position as to remain in engagement with the cylinder, I have provided a stop *z'* for 50 the counter-weight, this stop being located in such position as to keep the scraper out of engagement with the cylinder as is indicated at the left of Fig. 5.

As the impression cylinder revolves, the 55 intaglio plates on the cylinders *d*, *e* and *f* make a plurality of impressions in different colors. These plates receive ink in a manner which has been described and after the ink has been deposited upon each one, the cleaning blade *t* scrapes the surplus ink

from the surface of the intaglio plates for the purpose above set forth. As the surface of each plate cylinder makes its impression on the sheet on the impression cylinder and passes around in the direction shown by the 70 arrows, it is again cleaned by the cleaning blade *w*. This is, as has been stated, for the purpose of removing any ink which has been deposited upon the plates by the sheet itself, this sheet having been previously inked by 75 another roller carrying a different color. It will be seen, therefore, that by the employment of the principles set forth above, whether in the form illustrated or not, an efficient way of operating three-color printing and other presses with intaglio plates is 80 secured.

It is to be understood that while I have described a particular press for use with my invention and a particular form of mechanism for application to the press, I am aware that many modifications may be made in the mechanism and that it can be applied to many kinds of presses in accordance with the spirit of my invention as expressed in 90 the claims and consequently I do not wish to be limited to the exact construction shown, but

What I do claim and desire to secure by Letters Patent is:—

1. A printing press having means for supporting an intaglio plate movable to and from operative position, a cleaning device for said plate, means for yieldingly holding the cleaning device in position to engage 100 the printing surface of the plate when the supporting means is in operative position, said cleaning device being movable out of position, and means for holding the cleaning device out of contact with the plate when the supporting means is out of operative position.

2. A printing press having means for supporting a printing plate, said means being movable out of operative position, a cleaning device for the printing plate, and means for holding the cleaning device and plate out of contact with each other when said supporting means is out of operative position.

3. In a printing press, the combination of a plate holding means, a cleaning device adapted to engage the printing surface of the plate carried by the plate holding means, and a connection between said plate holding means and cleaning device whereby motion of the plate holding means will move the cleaning device out of engagement with the printing surface.

4. In a printing press, the combination of a plate holding device, a shaft mounted adjacent thereto, a cleaning device mounted on said shaft and adapted to engage the printing surface, and a roller connected with said shaft and resting on the printing sur-

face, said roller being located between said shaft and the point at which the plate engages the printing surface, whereby motion of the printing surface toward the roller will move the cleaning device out of engagement with the printing surface.

5. In a printing press, the combination of a plate cylinder, a shaft journaled adjacent thereto, a cleaning blade mounted on 10 said shaft, an extra shaft connected with said shaft for yieldingly holding the cleaning blade in engagement with said cylinder, and a roller connected with said shaft and bearing on said cylinder at a point between 15 the shaft and the point at which the blade engages the cylinder.

6. In a printing press, the combination of an impression cylinder, a plurality of plate cylinders mounted in position to engage 20 the impression cylinder, means for moving said plate cylinders out of engagement with the impression cylinder, a cleaning blade movably mounted adjacent to each plate cylinder and adapted to engage the 25 surface thereof, means for yieldingly holding said blades in engagement with the plate cylinders, and means for holding said blades out of engagement with the plate cylinders when said plate cylinders are moved 30 away from the impression cylinder.

7. In a printing press, the combination of an impression cylinder, a plurality of plate cylinders mounted adjacent thereto and adapted to engage the surface thereof, 35 means for moving said plate cylinders out of engagement with said impression cylinder, a cleaning blade movably mounted adjacent to each plate cylinder on the side toward which said cylinders move, means

for holding said blades in engagement with 40 said cylinders when the cylinders are in engagement with the impression cylinder, and means for holding said blades out of engagement with said cylinders when said cylinders are out of engagement with the 45 impression cylinder.

8. In a printing press, the combination of an impression cylinder, a plurality of plate cylinders mounted adjacent thereto and adapted to engage the surface thereof, 50 means for moving said plate cylinders out of engagement with said impression cylinder, a cleaning blade movably mounted adjacent to each plate cylinder on the side toward which said cylinders move, means 55 for holding said blades in engagement with said cylinders when the cylinders are in engagement with the impression cylinder, means for holding said blades out of engagement with said cylinders when said cylinders are out of engagement with the impression cylinder, additional cleaning blades 60 mounted adjacent to certain of said plate cylinders, means for normally holding said last mentioned blades in engagement with the plate cylinders when the latter are in engagement with the impression cylinder, and a stop for preventing the last mentioned blades from moving with the plate cylinders 65 when they are moved out of engagement with the impression cylinder.

In testimony whereof I have hereunto set my hand, in the presence of two subscribing witnesses.

H. A. WISE WOOD.
